ATTORNEY.

UNITED STATES PATENT OFFICE.

LEE KENT, OF HOT SPRINGS, ARKANSAS.

COMBINATION-HOOK.

SPECIFICATION forming part of Letters Patent No. 395,704, dated January 8, 1889.

Application filed April 18, 1888. Serial No. 271,075. (No model.)

To all whom it may concern:

Be it known that I, LEE KENT, a citizen of the United States, residing at Hot Springs, in the county of Garland and State of Arkansas, 5 have invented certain new and useful Improvements in Painters' Combination Pot-Hooks, of which the following is a specification.

My invention relates to improvements in 10 painters' combination pot-hooks, and particularly as an improvement in the hook patented to me by the United States January 24, 1888, No. 376,825.

In the accompanying drawings, Figure 1 is 15 a perspective view of my invention. Fig. 2 is a view showing it used as a handsaw-handle, and Fig. 3 showing it used as a can-opener.

My invention is described as follows:

Fig. 1 represents my improved hook complete, in which the blade A represents a putty-knife; B, a tack-puller; D and E, pot-hooks; F, a revolving glass-cutter journaled in the slot f in the arm of the pot-hook D.

C is a stage-fastener. The two converging 25 ends of the pot-hooks D E, leaving the opening I, make a glass-nipper; the point G, a screw-driver. The edge h on the extension H and the projection J, acting as a rest or fulcrum, together with the body of the tool, make 30 a can-opener. The flat head K is a tack-hammer and point-driver.

To use the tool for a can-opener, force the extension H through the top of the can up to the side projection, J. The edge h of the said

extension H is sharp, and the lower edge of 35 the said side projection is also sharp and rests on the top of the can, serving as a fulcrum. Work the tool backward and forward with a slight pressure forward, and it works well as a can-opener.

To use the tool as a saw-handle, the saw-blade must have a perforation near its heel and another perforation, the size and shape of the side projection, J, a proper distance from the heel. Secure the saw-blade to the 45 tool by passing the side projection, J, through the forward perforation and a screw-bolt, M, through the base of the pot-hook D and the rear perforation in the heel of said blade. Said rear perforation may be threaded, or a 50 tap-nut may be used on the threaded end of said screw-bolt.

Having described my invention, what I claim as new, and desire to secure by Letters Patent, is—

The painter's combination pot-hook herein described, provided with the putty-knife A, tack-puller B, tack-hammer K, glass-cutter F, glass-nipper I, can-opener H J, and screw-driver G, substantially as shown and described.

In testimony whereof I affix my signature in presence of two witnesses.

LEE KENT.
